UNITED STATES PATENT OFFICE.

JULIUS STEELE, OF CHICAGO, ILLINOIS.

DESIGN FOR A BOTTLE.

44,188.

Specification for Design.

Patented June 10, 1913.

Application filed January 23, 1913. Serial No. 743,877. Term of patent 14 years.

To all whom it may concern:

Be it known that I, JULIUS STEELE, citizen of the United States, residing at Chicago, in the county of Cook and State of Illinois, have invented a new, original, and ornamental Design for Bottles, of which the following is a specification, reference being had to the accompanying drawing, forming part thereof.

The figure is a perspective view of a bottle, showing my new design.

The body portion of the bottle, that is the portion between the base and the neck of

the bottle, is composed of alternating plain and curved surfaces.

I claim:

The ornamental design for a bottle, as shown.

In witness whereof I hereunto subscribe my name this 21st day of January, A. D. 1913.

JULIUS STEELE.
